United States Patent [19]

Kimura et al.

[11] Patent Number: Des. 313,226

[45] Date of Patent: ** Dec. 25, 1990

[54] **DIGITAL MULTIMEDIA INFORMATION EXCHANGE EQUIPMENT**

[75] Inventors: **Koji Kimura, Mitaka; Hideki Zenitani, Akishima, both of Japan**

[73] Assignee: **Fujitsu Limited, Kanagawa, Japan**

[**] Term: **14 Years**

[21] Appl. No.: **254,669**

[22] Filed: **Oct. 7, 1988**

[30] **Foreign Application Priority Data**

Apr. 15, 1988 [JP] Japan 63-15502

[52] U.S. Cl. D14/102; D14/240

[58] **Field of Search** D14/100, 102, 103, 107, D14/108, 109; D13/162, 184, 199; D6/509-511, 432, 446; 360/97-99, 137; 361/331, 332, 380, 381, 390-395, 399, 415, 426; 312/138.1, 208; 379/329

[57] CLAIM

The ornamental design for digital multimedia information exchange equipment, as shown.

DESCRIPTION

FIG. 1 is a front elevational view of digital multimedia information exchange equipment showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a top, front, right side perspective view thereof.

FIG. 3

FIG. 2

FIG. 1

FIG. 4

FIG. 5

FIG. 6

FIG. 7
